UNITED STATES PATENT OFFICE.

FRANK H. TRIMBLE, OF LANKERSHIM, CALIFORNIA.

DESIGN FOR A LIGHTING-FIXTURE WALL PLATE.

Application filed August 30, 1926. Serial No. 18,900. Term of patent 3½ years.

To all whom it may concern:

Be it known that I, FRANK H. TRIMBLE, a citizen of the United States, residing at Lankershim, in the county of Los Angeles and State of California, have invented a new, original, and ornamental Design for Lighting-Fixture Wall Plate, of which the following is a specification, reference being

had to the accompanying drawing, forming part thereof.

In the drawing, Figure 1 is a face view of the plate and Figure 2 is a side elevation.

I claim:

The ornamental design for a lighting fixture wall plate as shown.

FRANK H. TRIMBLE.
